UNITED STATES PATENT OFFICE.

JAMES S. LEAKE, OF SPENCER, VIRGINIA.

CHURN.

No. 796,847.

Specification of Letters Patent.

Patented Aug. 8, 1905.

Application filed May 25, 1905. Serial No. 262,260.

To all whom it may concern:

Be it known that I, JAMES S. LEAKE, a citizen of the United States, residing at Spencer, in the county of Henry and State of Virginia, have invented new and useful Improvements in Churns, of which the following is a specification.

This invention relates to churns in which the dasher shaft or staff is operated by a crank-rod and disk or wheel, the crank-rod being adjustably connected to the dasher shaft or staff and the disk or wheel to regulate or modify the extent of throw or stroke of the said shaft. The disk or wheel in the present construction of churn-operating mechanism has considerable weight and serves in a measure to counterbalance the moving parts and reduce to a minimum the resistance set up by the dasher, especially when the butter begins to form and after it has assumed the nature of a definite mass within the churn-body. The disk or wheel connected to the dasher shaft or staff is operated by sprocket wheel and chain gearing, the sprocket-wheels having such proportion that the one directly actuated by the operator will drive the remaining one at a greater rate of speed and materially obviate the tiresome work incident to churning, and this sprocket wheel and chain gearing cooperates with the weighted or heavy disk or wheel connected to the dasher shaft or staff to still further lighten the churning operation. The parts of the churn-operating devices are readily separable for convenience in packing, storing, or shipping the same and also for readily repairing any of the mechanical devices comprised in the organization.

Another material advantage in the present form of churn is that different sizes of churn bodies or receptacles to receive the dasher may be used to accommodate churning different quantities of cream, a lid or cover for the bodies or receptacles being used and applicable to a number of such bodies. The dasher shaft or staff is also readily removable as well as the lid or cover for the churn-body, and the latter is held in place by resilient attaching means connected thereto at diametrically opposite points and also to the frame structure of the churn.

Another important feature in the present churn structure is the provision of a trough-like holding means in which the churn body or receptacle is disposed and having a partition rising therefrom, at opposite sides of

which the operating devices are disposed and serve as a shield or protective means for the operator, as well as a stable support for the several mechanisms.

Other novel features of construction as well as advantages will be hereinafter more fully set forth.

In the drawings, Figure 1 is a perspective view of a churn embodying the features of the invention and showing the crank-rod in detached condition in dotted lines. Fig. 2 is a rear elevation of the churn, particularly showing the mechanism actuated by the operator and held by a partition, which serves as a shield or protective means for the operator, as well as a support for the several mechanisms. Fig. 3 is a transverse vertical section through the churn body or receptacle and the base structure for supporting the same, as well as the lid or cover, applicable to churn bodies or receptacles of varying dimensions, a part of the dasher shaft or staff and the dasher being also illustrated in this figure.

Similar numerals of reference indicate corresponding parts in the views.

The base structure of the churn consists of a trough-like support having a flat bottom 1 and sides 2, with the upper edges inclined downwardly or beveled, as at 3, toward the free end of the bottom 1. The dimensions of the base structure are such as to removably receive a churn body or receptacle of large dimensions and replaceable by other bodies or receptacles of smaller dimensions. The base structure is connected to a vertical partition or back 4, which is preferably solid or imperforate and rises to such an extent above the base structure as to dispose the mechanism directly actuated by the operator at a convenient elevation. This partition or back 4 serves as a means for supporting actuating mechanism, a part of said mechanism being on one side of the partition and the remaining mechanism on the reverse side. To the top of the partition or back 4 a ledge 5 is secured and projects horizontally over a portion of the base structure below and is provided with a hinged member 6, normally held closed by a suitable hook and eye 7, the ledge and the hinged member having arcuate recesses therein to form an opening for the loose reception of the dasher shaft or staff 8.

The sides 2 of the base structure have inner concaved clearance-recesses 9 to receive a churn body or receptacle 10 of maximum

dimensions within a comparatively reduced transverse or width extent of said base structure, and, as before set forth, the body or receptacle 10, as shown, is adapted to be replaced by various sizes of similar receptacles in accordance with the amount of cream treated or churned with material advantage in the churning operation, as well as convenience in the use of a number of churn bodies or receptacles in which the cream may be disposed. This provision for the substitution of churn bodies or receptacles of varying dimensions is further advantageous when it is desired to produce large and smaller quantities of butter and adapting the remaining part of the churn structure and operating mechanism for use with various receptacles without requiring a corresponding change in the proportions and dimensions of the complete churn organization. The churn body or receptacle 10 is held close to the partition or back 4 and is retained in place by the sides 2, and in applying and removing the same it may be pushed inwardly in the trough-like base structure or pulled outwardly from the latter.

A lid or cover 11 is used to close the top of the churn body or receptacle and is so proportioned that the same or a single lid or cover may be used with a number of receptacles varying in dimensions. The upper surface of the lid or cover is hollowed out regularly from the periphery inwardly toward the center, as at 12, to produce a drain-cavity lowest at the center, where an opening 13 is formed for the passage and free movement therethrough of the dasher shaft or staff 8. During the operation of the churn should any of the cream work upwardly through the opening 13 with the dasher shaft or staff 8 it will be retained in the drain-cavity and run or flow back into the churn body or receptacle through the said opening. In other words, any exudation of cream from the churn body or receptacle through the opening 13 in the lid or cover 11 will be prevented from splashing or running over the said lid or cover to the sides of the churn, and thereby the churning operation may be carried on with cleanliness. In many of the churns now in use the lid or cover is secured in place by fastening means which are frequently found difficult to release and expensive in application, and, furthermore, devoid of any yielding characteristics to permit the escape of gas generated during the churning operation within the churn body or receptacle. The present improved churn includes in its equipment simple devices for positively holding the lid or cover in place with a yielding pressure and also practically operative with churn bodies or receptacles differing in height. The preferred form of lid or cover fastening means consists of two eyes 14, secured at diametrically opposite points to the lid or cover and removably engaged by closely-coiled springs 15, having

hooks 16 at their upper ends for ready attachment to and separation from the eyes 14 and loops 17 at their lower ends secured to eyes 18, projecting from the outer portions of the sides 2 of the base structure, and at such distance below the upper edges 3 of said sides that the springs when detached may be thrown over and positioned entirely clear of the said upper edges 3 to avoid interference with the application and removal of the churn body or receptacle.

The dasher shaft or staff 8 has secured to the lower end thereof a common form of cross-blade dasher 19, of such dimensions that it will practically operate within churn bodies or receptacles varying in dimensions, and at a suitable elevation the dasher shaft or staff also has a series of openings 20 formed therein to receive the reduced extremity 21 of an upper angular arm 22, forming part of a crank-rod 23, the dasher shaft or staff being held positively in connection with the angular arm 22 by a thumb or wing nut 24, engaging the threaded end of the reduced extremity 21 to vary or modify the stroke of the dasher shaft or staff. The reduced extremity 21 may be fitted in any one of the openings 20, and this is particularly advantageous in view of the replacement of one churn body or receptacle 10 by another varying in height to insure a sufficiency of depth of stroke of the dasher within the said body. The crank-rod 23 is also adjustably secured at its opposite end to one of the spokes 25 of a wheel 26, which is of considerable weight and serves as a counterbalancing means to materially assist in the operation of the churn and relieve the operator of tiresome strain, especially when the butter is forming or has assumed a definite mass within the churn body or receptacle. The spoke 25 is formed with a series of radially-disposed openings 27, in either one of which the lower end of the crank-rod 23 may be secured in proportion to the adjustment of the opposite end of the crank-rod with respect to the dasher shaft or staff 8, suitable removable means, such as a thumb-nut or analogous device, being employed to secure the lower end of the crank-rod to the spoke 25. The wheel 26 is keyed to a shaft 28, passing transversely through the center of the partition or back 4 and disposed in metallic-bearing means secured to said back and providing a metallic surface for the support and movement of the shaft. On the opposite end of the shaft 28 and against the rear side of the partition or back 4 a small sprocket-wheel 29 is secured to rotate with said shaft. In alinement with the shaft 28 and located near the upper terminal of the partition or back 4 is a rearwardly-projecting rotatable stub-shaft 30, on which is fixed an enlarged sprocket-wheel 31, the sprocket-wheels 29 and 31 having a chain-belt 32 trained thereover, and the shaft 30 being provided with a crank-handle 33 for actuating the same and the sprocket-

wheel 31. This sprocket-gearing is positive in its operation and lightens the power required to actuate the dasher shaft or staff 8, particularly in view of the counterbalancing wheel 26. Another advantage of the use of this sprocket mechanism over directly meshing gears is that the mechanism can be more quickly started and will have a more positive operation. By the use of the enlarged sprocket-wheel 31 and the sprocket-wheel 29 of very much smaller dimensions the operator will be relieved of the necessity of rapid rotation of the shaft 30 without detracting in the least from the necessary reciprocation of the dasher shaft or staff 8. Both shafts 28 and 30 are mounted in similar bearings having disk faces or securing members 34 bolted through and through with respect to the partition or back 4.

The imperforate or solid partition or back 4 having the mechanism on the rear side thereof for direct actuation by the operator permits the latter to assume a shielded position with relation to the churn body or receptacle located on the opposite side of the partition or back, and any tendency of the contents of the churn body or receptacle to be forced upwardly through the opening 13 in the lid or cover 11 will not in the least affect the operator standing at the back of the churn.

If the dasher shaft or staff carrying the dasher be separated from the remaining mechanism for cleaning purposes or if such separation be required at any time in preparing the churn to operate or after the butter has been fully formed, it is obvious that the crank-rod 23 would hang or fall into a very inconvenient position and interfere with the desired assemblage of the churn body or receptacle with relation to the base structure or removal of such body from this structure. To obviate this disadvantage, a guard 35 is secured on the partition or back 4 above the wheel 26, said guard being preferably of rectangular form and having such transverse extent that the crank-rod will move therein without contact with any portion thereof. When the crank-rod is disconnected from the dasher shaft or staff 8, it will be held in elevated position by the guard, no matter if the operating mechanism be set in motion, in view of the angular arm 22 at the upper terminal of said crank-rod, said angular arm preventing the crank-rod from drawing downwardly through the guard, as clearly shown in dotted lines in Fig. 1.

From the foregoing it will be seen that the main structural advantages reside in the provision of an imperforate or solid vertical partition or back rising from a trough-like base structure, the capability of using churn bodies or receptacles having varying dimensions within the same churn structure and without modifying the proportions or dimensions of the latter, the positive actuating mechanism

which relieves the operator of considerable tiresome work, and the general convenience and simplicity of the entire organization and the facility with which the several parts may be assembled and disconnected.

Having thus described the invention, what is claimed as new is --

1. A churn having a base structure with a flat upper surface and adapted to hold churn-bodies of different sizes, a lid or cover for common application to the different churn bodies or receptacles disposed in the base structure, longitudinally expansible and contractible fastening devices detachably connected to the lid or cover at diametrically opposite points and also to the base structure, a dasher-shaft movable through the lid or cover and having a dasher on its lower extremity, and mechanism for operating the dasher-shaft.

2. A churn having a trough-like base, the bottom of which has a flat upper surface, the said base structure being adapted to receive churn-bodies of different sizes, a lid or cover for common application to the different sizes of churn-bodies that may be disposed in the base structure, longitudinally expansible and contractible fastening means removably attached to diametrically opposite portions of the lid or cover and to the base structure, a dasher-shaft having a dasher thereon and vertically movable through the lid or cover and elevatable with the latter when detaching the dasher-shaft and lid or cover from a churn-body, and mechanism for operating the dasher-shaft, the fastening-means being movably connected to the outer portions of the sides of the trough-like base structure.

3. A churn having a trough-like base structure, a body or receptacle removably disposed in the base structure and replaceable by other like devices varying in vertical and transverse dimensions, a single lid or cover common to all the receptacles that may be disposed in the trough-like structure, longitudinally expansible and contractible fastening devices removably attached to opposite portions of the lid or cover and to the trough-like structure, a dasher-shaft vertically movable through the lid or cover and having a dasher thereon, and mechanism for operating the dasher-shaft.

4. A churn having a trough-like base structure, a body or receptacle removably disposed in the base structure and replaceable by other like devices varying in vertical and transverse dimensions, a single lid or cover common to all the receptacles that may be disposed in the trough-like structure, longitudinally expansible and contractible resilient fastening devices removably attached to opposite portions of the lid or cover and to the trough-like structure, a dasher-shaft vertically movable through the lid or cover and having a dasher thereon, and mechanism adjustably attached to the dasher-shaft for operating the latter.

5. A churn having a trough-like structure,

a body or receptacle removably disposed in the base structure and replaceable by other like devices varying in vertical and transverse dimensions, a single lid or cover common to all the receptacles that may be disposed in the trough-like structure, longitudinally expandible and contractible resilient fastening devices removably attached to opposite portions of the lid or cover and to the trough-like structure, a dasher-shaft vertically movable through the lid or cover and having a dasher thereon, and mechanism for operating the dasher-shaft including a wheel and a crank-rod, the crank-rod being adjustably attached to the wheel and to the dasher-shaft.

6. A churn having a trough-like base structure including opposite sides with upper downwardly-inclined edges, a churn body or receptacle removably insertible in the base structure between the sides and adapted to be replaced by similar devices varying in vertical and transverse dimensions, a lid or cover for the body or receptacle, yielding fastening devices having terminal means detachably connected to opposite portions of the lid or cover and also to the sides of the base structure, the adjustment of said fastening devices being obtained by longitudinal expansion and contraction thereof, a dasher-shaft vertically movable through the lid or cover and having a dasher on the lower extremity thereof, and mechanism attached to the dasher-shaft for operating the latter.

7. A churn having a base structure having a solid partition rising therefrom, a body removably held in said structure, a lid or cover for the body, a dasher-shaft vertically reciprocable through the lid or cover and having a dasher on its lower extremity, mechanism for operating the dasher-shaft and including a crank-rod having an upper angular arm removably attached to the dasher-shaft and a wheel to which the opposite extremity of the crank-rod is connected, and a guard secured to the partition and projecting outwardly from the latter and located above said wheel and

through which the crank-rod extends, the said guard preventing the crank-rod from falling over the lower portion of the churn structure when detached from the dasher-shaft.

8. In a churn, a trough-like base structure having an imperforate partition rising therefrom and forming the back therefor, a body or receptacle removably disposed in the base structure the latter having the sides reduced toward the open end thereof and which is located opposite the partition, a dasher shaft disposed in reciprocable relation to the body and having a dasher on its lower extremity, a ledge at the upper extremity of the partition and provided with a hinged member to removably receive the dasher-shaft, a wheel held adjacent to the side of the partition nearest the body or receptacle and provided with a crank-arm which is attached to the dasher-shaft, and operating mechanism on the rear side of the partition for setting the wheel and crank-rod in motion.

9. In a churn, the combination of a base structure having an open end toward which the said structure gradually reduces, a body or receptacle removably disposed in said base structure, a solid partition or back rising from the rear of the base structure and forming a back for the latter, a lid or cover for the body or receptacle, a dasher shaft or staff vertically movable through the lid or cover and having a dasher thereon in the receptacle, mechanism directly attached to the dasher-shaft held on the side of the partition or back nearest the body or receptacle, and mechanism on the reverse side of the partition or back for actuation by the operator, the partition or back serving as a shield for the operator and also to separate the mechanism carried thereby.

In testimony whereof I have hereunto set my hand in presence of two subscribing witnesses.

JAMES S. LEAKE.
